UNITED STATES PATENT OFFICE.

JOSEPH J. STEPHENS, OF LAMONT, MICHIGAN.

METAL BUILDING AND STRUCTURAL UNIT THEREFOR.

Application filed May 1, 1924. Serial No. 710,305.

To all whom it may concern:

Be it known that I, JOSEPH J. STEPHENS, a citizen of the United States, residing at Lamont, county of Ottawa, State of Michigan, 5 have invented certain new and useful Improvements in Metal Buildings and Structural Units Therefor, of which the following is a specification.

This invention relates to improvements 10 in metal buildings and structural units therefor.

The main objects of this invention are:

First, to provide an improved metal building structure in which the walls are well 15 adapted to exclude heat and cold.

Second, to provide an improved metal wall structure for buildings in which the units are easily assembled and have joints which effectively exclude moisture.

20 Third, to provide improved structural units for buildings which are very strong in proportion to the weight of the material entering into the same.

Objects pertaining to details and economies of my improvements will definitely appear from the detailed description to follow.

I accomplish the objects of my invention by the devices and means described in the 30 following specification. The invention is clearly defined and pointed out in the claims.

A structure which is a preferred embodiment of my invention is clearly illustrated in the accompanying drawing forming a 35 part of this application, in which:

Fig. I is a fragmentary perspective view of a building embodying the features of my invention, no regard being paid to proportions and only such parts being shown as are 40 deemed necessary to illustrate my improvements.

Fig. II is an enlarged fragmentary plan view of the wall and one of the joists.

Fig. III is a detail vertical section on a 45 line corresponding to line 3—3 of Figs. I and II.

Fig. IV is a fragmentary perspective view of the parts of one of the structural beam units in disassembled relation.

50 Fig. V is a perspective view of one of the coupling members.

Fig. VI is a perspective view of one of the rafter saddles or supporting brackets.

55 Fig. VII is a fragmentary side view of a coacting pair of rafters.

Fig. VIII is a perspective view of one of the rafter coupling members.

Fig. IX is a perspective view of one of the fasteners.

In the drawing similar reference numerals indicate similar parts throughout the several views.

Referring to the drawing, the studding 1, the joists 2 and the rafters 3 are all structurally the same except as to details of the 60 coupling by means of which certain parts are connected. These structural units are formed up of the channel members 4 disposed back to back and connected by the tie members 5 which have in-turned flanges 6 at their edges embracing the arms or flanges 7 of the channel members, thus forming 65 structural units of I-beam section.

The studding 1 has upright partition supporting channels 8 secured thereto by means 70 of the lugs 9 which are struck out from the upper and lower ends of the studding and folded within the channels, thus providing the studding with oppositely facing partitions 75 engaging channels.

The edges of the wall panels 10 are folded outwardly to provide outwardly disposed flanges 11 and are then folded inwardly to provide the inwardly disposed channels 12, the folds being of S-cross section as shown 80 in Fig. II. The inwardly disposed channels 12 are engaged with the arms of the studding while the outwardly facing channels are engaged with the inturned flanges 13 of the joint members 14, thus clamping the 85 wall panels to the studding and providing an effective closed and sealed joint.

The partition panels 15 are of asbestos board or other non-conducting material and these are supported with their edges within the channels of the folders 8. This not only secures insulated air chambers but also the insulated partitions are provided. The wall panels preferably have openings 16 at the top and bottom thereof to permit circulation 90 of the air, thereby avoiding sweating of the walls. The walls are provided with top plates 19.

The joists 2 are provided with coupling members 20, these coupling members being 100 of U-shape and are disposed with their arms 21 between the channel members 4 and the tie members. These coupling members are secured by means of the fasteners 22 having 105 prongs 23 arranged through holes 24 in the 110

superimposed parts, the prongs being folded down as shown in Fig. III.

The bight or cross portions of the coupling members have inturned flanges 25 adapted to engage the studding as shown in Fig. II, the inner panels terminating or being recessed to receive these coupling members. These superimposed parts are provided with openings 24 to receive the fasteners as shown in Fig. III.

The rafters 3 are provided at their inner ends with U-shaped coupling members 26 which are arranged with their arms between the tie members of the channel members and secured by fasteners 22. The bight portions of these coupling members abut and are connected as shown in Fig. VII.

The rafters are secured to the walls by means of the triangular saddles 27 having horizontal portions 28 adapted to rest upon the top of the walls, and downwardly projecting extensions 29 adapted to engage the inner sides of the wall. The angle of the inclined side 30 corresponds to the angle of 25 the rafter and this portion has flanges 31 embracing the arms of the rafter units and secured thereto by means of fasteners 28.

With the parts thus arranged I secure a wall which is well adapted to exclude heat 30 and cold and one which does not sweat under changing atmospheric conditions. The parts are easily assembled and disassembled.

I have not in the accompanying drawings 35 attempted to show the parts in their relative proportions but it is believed that the disclosure made will enable those skilled in the art to embody or adapt my improvements as may be desired.

Having thus described my invention what 40 I claim as new and desire to secure by Letters Patent is:—

1. In a wall structure, the combination of 45 studding units comprising channel members disposed back to back and tie members having inturned flanges at the edges thereof embracing the flanges of said channel members providing units of I-cross section, wall panels having their vertical edges conformed 50 to an S cross section providing inwardly disposed channels engaging the arms of the studding units and outwardly facing joint flanges, joint members having inturned flanges engaging the joint flanges of said 55 wall panels, channeled partition panel holders disposed on the webs of said studding units having lugs struck therefrom and engaged within the ends of said holders, and partition panels disposed with their edges 60 in said holders.

2. In a wall structure, the combination of 65 studding units comprising channel members disposed back to back and tie members having inturned flanges at the edges thereof embracing the flanges of said channel

members providing units of I-cross section, wall panels having their vertical edges conformed to an S-cross section providing inwardly disposed channels engaging the arms of the studding units and outwardly facing joint flanges, and joint members having inturned flanges engaging the joint flanges of said wall panels. 70

3. In a wall structure, the combination of 75 studding units comprising channel members disposed back to back and tie members having inturned flanges at the edges thereof embracing the flanges of said panel members providing units of I-cross section, wall panels having channels at their vertical 80 edges engaging said studding units, joint pieces connecting said panels, channeled partition panel holders disposed on the webs of said studding units to face outwardly, the channel members of said studding units having lugs struck therefrom and engaged within the ends of said holders, and partition panels disposed with their edges in said holders. 85

4. In a wall structure, the combination of 90 studding units comprising channel members disposed back to back and tie members having inturned flanges at the edges thereof embracing the flanges of said panel members providing units of I-cross section, wall panels having channels at their vertical edges 95 engaging said studding units, and joint pieces connecting said panels.

5. In a wall structure, the combination of 100 studding units of I-cross section, wall panels having their vertical edges conformed to an S-cross section providing inwardly disposed channels engaging the arms of the studding units and outwardly facing joint flanges, joint pieces having inturned flanges engaging the joint flanges of said wall panels, channeled partition panel holders disposed on the webs of said studding units to face laterally, and partition panels disposed with their edges in said holders. 105

6. In a wall structure, the combination of 110 studding units of I-cross section, wall panels having their vertical edges conformed to an S-cross section providing inwardly disposed channels engaging the arms of the studding units and outwardly facing joint flanges, and joint pieces having inturned flanges engaging the joint flanges of said wall panels. 115

7. In a wall structure, the combination of 120 flanged studding units, wall panels having their vertical edges conformed to S cross section providing inwardly opposed channels engaging said studding units and outwardly facing joint channels, and joint strips having inturned flanges engaging the said joint flanges of said wall panels. 125

8. In a wall structure, the combination of 130 flanged studding units, wall panels having their vertical edges conformed to S cross

section providing inwardly opposed channels engaging said studding units and outwardly facing joint channels, and joint members engaging the said joint flanges of said wall panels.

9. In a wall structure, the combination of studding units comprising channel members disposed back to back and tie members having inturned flanges at the edges thereof 10 embracing the flanges of said panel mem-

bers providing units of I-cross section, and partition panel holders disposed on the webs of said studding units to face outwardly, the channel members of said studding units having lugs struck therefrom and engaged 15 with said holders.

In witness whereof I have hereunto set my hand.

JOSEPH J. STEPHENS.
